CLAIM

The ornamental design for a bifurcated slow feed bowl, as shown and described.

DESCRIPTION

FIG. 1 is an isometric perspective view of a bifurcated slow feed bowl in accordance with our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a cross section taken along line 8-8 of FIG. 6 thereof; and,

FIG. 9 is a cross section taken along line 9-9 of FIG. 6. The broken lines in the FIG. 7 view depict environmental features for illustrative purposes only and form no part of the claimed design.
